UNITED STATES PATENT OFFICE

SALVATORE SCOGNAMILLO AND PAUL ARNDT, OF NEW YORK, N. Y.

ELECTRON DISCHARGE DEVICE

Application filed June 25, 1928, Serial No. 288,172. Renewed July 3, 1931.

This invention relates to improvements in electron discharge devices, one object of the invention being the provision of a peculiar construction and mounting of the anode or filament in conjunction with a heating cathode, whereby the amount of current emanating from the anode and the efficiency in the discharge of electrons is determined by the surface capacity of the intermediate cathode 10 which, in the present instance, as is the case with the anode, has its operating surface materially increased, the said cathode acting as a permanent negative.

A further object of this invention is the provision of an electron discharge device of a type especially adapted for power amplification and whereby alternating current may be used for the filament or anode.

With the present construction, the detailed arrangement of the electron discharge device as particularly set forth and described in our co-pending application filed April 9, 1928, Serial No. 268,705, is employed, in conjunction with a novel arrangement and construction of anode and permanent negative cathode, thus providing a means whereby the construction shown in said pending application as a detector and amplifying tube may be used as a power amplifying tube.

20 In the accompanying drawings:—

Figure 1 is a vertical central sectional view through the preferred form of the present electron discharge device;

Figure 2 is a section taken on line 2—2 thereof;

Figure 3 is a perspective view of the plural cathode used in the present construction;

Figure 4 is a cross-section through one of the grid elements of the present device;

Figure 5 is a bottom plan view of the base showing the terminal points thereof;

Figure 6 is an enlarged detail sectional view through the upper end of the cathode, as shown in Figure 3, with the heat-resisting insulating cover for each compartment thereof;

Figure 7 is an electric diagram of one form of power amplifying circuit to be used in connection with the present electron discharge device;

Figure 8 is a view similar to Figure 1 of a

slightly modified form of the present invention;

Figure 9 is a section taken on line 9—9 of Figure 8;

Figure 10 is a detail plan view of one of the 55 members of the grid of the present device;

Figure 11 is a section taken on line 11—11 thereof.

Referring to the drawings and more particularly to Figures 1 to 7, inclusive, the numeral 12 designates the base of the evacuated tube 13. Mounted in the base and enclosed within the tube are two insulating supports 14 and 15 for the respective parallel portions 16 and 17 of the filament, the looped upper end of which is supported in an insulating member 18 which is made in the form of a yoke and is itself supported by a standard 60 19, the lower end of which is carried by the base 12. Thus the filament is divided into two 65 heating elements 16 and 17 which are disposed in parallel relation to each other, the purpose of which will presently appear.

The cathode 20 comprises a pair of tubular 70 chambers 22 and 23 connected by a pair of superposed plates 21 of the same height as said tubular chambers. As shown, each of the plates 21 is bent adjacent its vertical edges 75 to form channels of substantially semi-circular cross-section, and the plates are secured together by rivets with their channels in opposed relation to form the chambers 22 and 23.

A pair of sockets are formed at the lower 80 horizontal edges of the plates 21, as by depressions in the opposed faces of said plates, to receive the upper ends of a pair of supporting wires 25 and 25', which, in turn, are supported from the base 12.

As clearly illustrated, the heating elements 16 and 17 of the filament are disposed through and centrally of each of the chambers 22 and 23, which, in turn, are closed at their top by means of tubular caps 26, each 90 one of which surrounds its adjacent portion of the filaments 16 or 17 and is composed of a heat-resisting insulating material.

It will thus be seen that by this arrangement the efficiency of the present electron 100

discharge device will be determined by the amount of current emanating from the filament, and the efficiency in the discharge of the electrons is also determined by the surface capacity of the intermediate double cathode 20 and its respective chambers 22 and 23. By this construction, the efficiency of the tube is greatly increased due to this arrangement of the filament and cathode which gives an amplified area for the discharge of electrons which will more or less depend on the quantity of current emanated by the filament. By increasing the heating portions of the filament in the present instance substantially doublefold, the efficiency is doubled and is greatly increased in the discharge of electrons from the filament to the cathode without distortion or choking effect.

The remaining construction of the present electron discharge device is similar to that shown in the co-pending application above mentioned and consists primarily of elongated open members or plates 28 having apertures 29 for the reception of terminal and supporting rods 30 and 30', while a surrounding shell 31 is properly supported by rods or terminal supports 32 and 33 in the base 12.

The two filament-carrying supports 25 and 25' are connected to two plugs or pins F, F', 30 while the support 25 for the cathode 20 is connected to a plug or pin 25^a. The grid support 30 is connected to a plug or pin G, while the plate support 33 is connected to a plate pin or plug P.

35 Thus, with this type of electron discharge device, as in our previous construction, five pins, prongs or plugs are employed in installing the present construction.

In Figure 7 an electrical diagram is shown 40 with the present electron discharge devices in diagram therein and in which three of such discharge devices are installed, but the installation of the present tube is in no wise limited to this particular circuit arrangement, and the same is only shown as one example of obtaining the desired results in a power amplifying circuit with the present type of electron discharge device.

50 In this diagram, an alternating current step-down transformer T is employed to step down the alternating current voltage of, say, 110 volts to 5 volts, for delivery to the various filaments of the three electron discharge devices, while the respective plates and grids and the cathodes 20 are connected to be affected by the direct current voltages, as illustrated.

In the construction shown in Figures 8, 9, 55 10 and 11, each element as relates to the anode and double cathode 20 is identical, the only difference being that the grid elements 28' are provided with restricted portions 28" which conform more nearly to the exterior contour of the cathode 20, the plate 31 being

identical, and the wiring being identical to the construction previously described.

From the foregoing description, taken in connection with the drawings, it is evident that with this peculiar arrangement and construction an alternating current power amplifying electron discharge device is produced and by means of which the surface capacity is increased, and, therefore, the efficiency, without increasing the current consumption, 70 this electron discharge device consisting primarily of a concealed glow filament extending through two combined intermediate cathodes.

What is claimed is:—

1. An electron discharge device, including 80 a cathode comprising a pair of metallic plates each having a channel in one of its faces adjacent each of its ends and secured together face-to-face with their channels disposed opposite to one another and forming a pair of parallel chambers, and a filament having a pair of parallel portions extending, respectively, through said chambers.

2. An electron discharge device, including 90 a base, an evacuated vessel carried by said base, a cathode supported by the base and having a double thickness relatively flat connecting portion and a pair of open-ended tubes, one at each end of the connecting portion, and a filament having a pair of parallel portions extending through said tubes and supported from said base.

3. An electron discharge device, including 100 a base, an evacuated vessel carried by said base, a cathode comprising a pair of parallel tubular metallic chambers and a connecting portion of double thickness between said tubular chambers and of the same length as the latter, a substantially U-shaped filament of which the branches extend through and are encased within said tubular chambers and have their terminals mounted in the base, and a cover of heat-resisting electrical insulating material fitted in the upper end of each of said chambers and surrounding the adjacent portion of the filament therein.

4. An electron discharge device having a base, a filament in loop form having its terminals mounted in the base, a standard mounted in the base, an insulator member carried by the free end of the standard and encasing the connecting portion of the loop of the filament, and a two chambered cathode carried by the base and having the parallel portions of the loop extending through said chambers with the insulator member above the cathode.

In testimony whereof we have hereunto set our hands.

SALVATORE SCOGNAMILLO.
PAUL ARNDT.
